THE NORRIS PETERS CO., PHOTO-LITHO., WASHINGTON, D. C.

UNITED STATES PATENT OFFICE.

WILLIAM C. CORTELYOU, OF OBLONG, ILLINOIS.

COMBINED SKIRT-CLASP AND WAIST-RETAINER.

SPECIFICATION forming part of Letters Patent No. 699,286, dated May 6, 1902.

Application filed May 16, 1901. Serial No. 60,506. (No model.)

To all whom it may concern:

Be it known that I, WILLIAM C. CORTELYOU, a citizen of the United States, residing at Oblong, in the county of Crawford and State 5 of Illinois, have invented a new and useful Combined Skirt-Clasp and Waist-Retainer, of which the following is a specification.

This invention relates to a combined skirt-clasp and waist-retainer; and the object of the 10 invention is to present a device of the character specified which will be thoroughly effective for keeping the skirt of a dress and a shirt-waist assembled in use or to keep the skirt and basque securely assembled and in 15 which accidental release or separation of the parts of the device in use will be entirely obviated.

The invention consists, generally stated, in a two-membered device, one comprising an 20 eye-plate and the other a hook-plate, these parts to be associated with the band of the skirt and to be brought into engagement with each other in use. Combined with the hook member is a locking device, the same in operation preventing accidental separation of 25 the two plates in use, the locking device itself being held against movement by being engaged with loops or eyes formed at the waist-line in the back of the waist or by the employment 30 of a plate secured to the back of the waist to be engaged by the hooks of the locking device. The members of the fastener are to be shaped to conform to the contour of the waist of the user, so that in use no inconvenience 35 will be felt. The hooks on the hook-plate for engaging the openings in the eye-plate are formed by stamping out a series of lengths of metal constituting the hooks, the hook at one end of the plate being by preference 40 formed by reducing that end of the plate to a width corresponding to that of the hook and then turning the hook over to occupy the same plane as the other hooks. This latter procedure is adopted for the reason 45 that it renders the construction of the plate cheaper and also reduces its length, as where one of the end hooks is to be stamped up from the metal there must be a wall left to one side of the hook for support, and this extra metal 50 forming the wall is entirely unnecessary and is obviated by the procedure described. The other hook at the opposite end of the hook-

plate is formed by slitting the metal to form the hook and then bending this hook up so that its end terminates with the end of the 55 plate, this arrangement further operating to shorten the length of the plate, thereby reducing its weight and saving in metal in its construction. The eye-plate is provided with openings or eyes corresponding in number to 60 the hooks on the hook-plate and is formed in one edge with a plurality of incuts or depressions to be engaged by the locking device, the object of the incuts being to permit the hook of the locking device engaging the recesses 65 to lie flush with the upper edges of the two plates when assembled.

The device as a whole is constructed with a view to simplicity of construction, durability and efficiency in use, and cheapness of 70 production. Furthermore, from its construction and the manner in which it is assembled with the garment it will not present an attachment that will prove unsightly, and by provision of suitable means for attachment 75 to a garment, as will hereinafter appear, when once so assembled it will be held securely in place.

Further and more specific details of construction will be hereinafter fully described, 80 and pointed out in the claims.

In the accompanying drawings, forming a part of this specification, and in which like numerals of reference indicate corresponding parts, I have illustrated a form of embodiment of my invention capable of carrying my ideas into effect, it being understood that the same may be modified or changed in many points of its construction without departing from the spirit of the invention, and 90 in these drawings—

Figure 1 is a view in perspective of a garment exhibiting my device attached to the waist thereof. Fig. 2 is a view in sectional plan showing the manner in which the members of the waist are held assembled. Fig. 3 is a detached detail view in perspective of the hook-plate. Fig. 4 is a similar view of the eye-plate. Fig. 5 is a similar view of a reinforcing-plate to be employed in connection 95 with a waist to be engaged by the hooks of the locking device. Fig. 6 is a detached detail view of one of the pivoted hooks for engaging the waist. Figs. 7 and 8 are frag-

mentary detail views showing two different ways in which the device may be attached to the waistband.

Referring to the drawings, 1 designates the hook member, and 2 the eye member. The hook member is constructed of a piece of thin sheet metal and is formed with a plurality of hooks, in this instance three, formed of the metal of the plate and therefore integral therewith, although they may be secured thereto. As before pointed out, in order to shorten the plate, thus to reduce weight and saving in the use of metal, one end hook 3 is formed by a tongue stamped from the end of the plate and bent over to form the hook and the other end hook 4 by slitting the ends of the metal to form a tongue and bending this tongue up to form a hook, the hook terminating practically with the end of the plate. The center hook 5 is formed by stamping up a tongue in a manner that will be readily understood. It is to be understood that I do not limit myself to the exact number of hooks herein shown, as their number may be increased or diminished without departing from the spirit of the invention. On the opposite side of the hook-plate 1 from that on which the hooks project are pivoted two hooks or catches 6 and 7, the hook 6 being held assembled with the plate 30 by a pivot 8 and being provided with a hook or catch 9, extending parallel with the face of the plate, and with a rearward-projecting hook or catch 10 to engage with recesses 11 and 12, respectively, formed in the upper edge of the plates 1 and 2. As herein shown, the plate 1 is only provided with one recess, while the plate 2 is provided with two or more, the object of this being to permit the longitudinal adjustment of the members with relation to each other, so as to loosen or tighten the waistband, as may be found necessary. The recesses 11 and 12 are of such depth that when the hook 10 is closed down upon the upper edges of the plates it will lie flush with the said upper edges, thereby obviating the presentation of an obstruction. The hook 7 is pivoted to the plate 1 by a rivet 13, and its hook portion 14 also lies parallel, or approximately so, with the face of the plate 1, these 45 hooks to engage with openings similar to buttonholes formed in the waist-line at the back of the waist, as shown at 15, or instead of these openings braid eyes or ordinary eyes may be secured to the waist to be engaged by hooks, as shown at 16.

In order to impart additional stability in connection with the hooks 6 and 7 and the waist, I may employ a metallic plate 17, this to be placed on the inside of the waist-line 60 and to be provided with openings 18 to be engaged by the hooks 6 and 7, the plate being held assembled with the waist by threads passed through openings 19 at the sides and ends. When this plate is employed, tearing 65 of the goods, as from the strain from the hooks 6 and 7, will be obviated. While this plate has points of advantage, as pointed out,

the invention is not to be limited to the employment of this, as the plate may be omitted and the hooks 6 and 7 caused to engage with 70 the buttonholes or braid loops or eyes, as before stated.

The plates 1 and 2 are provided with openings 20 along their sides and ends through which threads are passed to secure them to 75 the waist. The eyes 21 in the plate 2 are formed by stamping out a sufficient length of metal for the purpose, as will be readily understood.

When this device is used with a skirt and 80 shirt-waist, the hook-plate is fastened to the left-hand side of the skirt, with the hooks passed through holes in the skirt-band provided for the purpose, and the eye-plate is secured to the right-hand side of the skirt. 85 When the two plates are brought into engagement with each other, the locking-hook 6 is turned to position, and the plates are thus held securely assembled against accidental separation, the hooks 6 and 7 being then 90 brought into engagement with openings or the like provided in the waistband, as described. Where the device is used with a skirt and a basque, the application of the parts is exactly reversed, as will be readily 95 understood.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages 105 of the invention.

What I claim is—

1. A skirt-clasp and waist-retainer comprising a hook-plate and an eye-plate, pivoted waist-supporting hooks carried by the 110 hook-plate, and locking means carried by one of the pivoted hooks to embrace and hold the two plates assembled.

2. A skirt-clasp and waist-retainer comprising a plate provided with a plurality of 115 hooks, a plate having a plurality of eyes to engage the hooks, and two pivoted waist-supporting hooks carried by one of the plates, one of the latter hooks having a catch to embrace the upper edges of the two plates to 120 hold them assembled against accidental separation.

3. A skirt-clasp and waist-retainer comprising two plates one of which is provided with a plurality of eyes, and the other with 125 a plurality of hooks to engage the eyes, the latter plate carrying on the side opposite that on which the hooks are arranged two pivoted hooks to engage with openings in the waist of the garment, one of the hooks being provided with a curved projection to bear upon the upper edge of the two plates and thus hold them locked against accidental separation. 130

4. A skirt-clasp and waist-retainer com-

prising two plates one of which is provided with a plurality of eyes, and with incuts or depressions upon its upper edge, and the other provided with rigid hooks extending outward from the face of the plate, and with an incut or depression upon its upper edge and with two pivoted hooks arranged on the opposite side of the plate to that carrying the rigid hooks, one of the hooks being provided with a curved offset to engage with the depressions formed in the upper edges of the two plates.

5. A waist provided at the waist-line with a perforated plate secured thereto, in combination with a skirt carrying a plate provided with hooks to engage with the perforations of the waist-plate, the second-named plate being provided with outwardly-extending hooks, a third plate carried by the free end of the skirt 15 to engage the outwardly-extending hooks, and locking means carried by one of the first-

named hooks and the second-named plate for holding the two plates assembled.

6. A device of the class described, comprising two interlocked members, pivoted locking means to hold the two members in interlocked relation, and means carried by the locking means for supporting the skirt. 25

7. A device of the character described, comprising a pair of members having detachable interlocking means, a pivotal locking device carried by one of the members and constructed to hold the latter against separation when interlocked, and a pivotal support carried by the outer side of the said member. 30 35

In testimony that I claim the foregoing as my own I have hereto affixed my signature in the presence of two witnesses.
